APPARATUS FOR HANDLING HOSIERY

Clarence Webb Minton, Nashville, Tenn., assignor to Morpul, Incorporated, Greensboro, N.C., a corporation of North Carolina

Filed May 17, 1961, Ser. No. 110,801

2 Claims. (Cl. 223—39)

This invention relates to the handling of hosiery and is particularly, although not exclusively, applicable to the handling of women's hosiery incidental to inspection thereof.

Women's hosiery usually must be positioned upon various forms, for instance inspecting or boarding forms, at least several times as manufactured under present procedures. The facility and rapidity with which each such positioning can be effected therefore has an appreciable effect upon the cost of manufacture of the hosiery. Additionally, these factors have a direct bearing upon the number of hose that an operator or employee can process before becoming unduly fatigued.

Heretofore, the positioning of women's hosiery upon inspection forms has been a particularly time-consuming, cumbersome and fatiguing operation. It has customarily been performed by an operator placing the welt opening of each hose over the free end of a form, and then pulling the welt of the hose toward the distal end of the form until the entire hose is donned thereon. Since the hosiery may have a length of some three feet, this requires considerable movement on the part of the operator. Such movement is time consuming and additionally, when repetitious, is extremely fatiguing. Consequently, both the morale and the production of employees performing this operation have frequently been poor.

With the foregoing in mind, a primary object of this invention is the provision of apparatus for handling hosiery as discussed above with greater rapidity, facility, and without excessive operator fatigue. Another object, related to and stemming from the foregoing, is the reduction of hosiery manufacturing and/or processing costs.

Another related and more specific object is the elimination of the necessity for excessive operator movement in the positioning of hosiery upon hosiery forms. When employing the teachings of the instant invention, the hands and arms of an operator need move but a matter of inches to position hose upon a form, by reason of which the positioning can be accomplished more quickly and easily than has heretofore been possible.

A still more specific object is the provision of hosiery handling apparatus including an elongate hosiery form that is mounted for reciprocatory movement along a predetermined path and for rotative movement about its longitudinal axis. It has been found that apparatus including a hosiery form thus movable is particularly satisfactory and advantageous for the inspection of women's hosiery during the course of their manufacture.

Still other objects and advantages will be in part evident and in part pointed out hereinafter in the following description of an illustrative embodiment of the invention, which should be read in conjunction with the accompanying drawings, in which—

FIGURE 1 is a perspective view of the apparatus in use, the hosiery form thereof being shown in its retracted position by solid lines and in its projected position by dotted lines;

FIGURE 2 is an enlarged fragmentary sectional view taken substantially along line 2—2 of FIGURE 1;

FIGURE 3 is an enlarged fragmentary side view of the bracket and associated components secured to the lower end of the hosiery form shown in FIGURE 1;

2

FIGURE 4 is a section taken substantially along line 4—4 of FIGURE 3, dotted lines being employed to illustrate the components shown in another relative rotative position;

5 FIGURE 5 is an enlarged plan view, partially in section and taken substantially along line 5—5 of FIGURE 1, of the treadle-actuated valve of the apparatus; and

FIGURE 6 is a schematic view of the fluid pressure system of the apparatus.

In the illustrative embodiment of the drawings, the invention is shown as applied to the operation of initial or preliminary inspection of women's hosiery, that is to the inspection thereof immediately after knitting and prior to the toe portion of the hose being closed by seaming or looping. It will be appreciated, however, that this is for purposes of illustration only, and that the invention is applicable to other operations. Similarly, although the apparatus of the illustrative embodiment shown in the drawings is vertically disposed, it will subsequently be apparent that apparatus embodying the invention might be otherwise oriented without departing from the teachings herein.

Referring now more particularly to the drawings, the apparatus shown in FIGURES 1 and 2 includes a supporting base 10 having a flanged sleeve portion 12 and an integral annular portion 14. Base 10 is secured by any suitable means, such as by bolts 16 extending through annular portion 14 thereof, to a frame 18, which may be the floor of a mill or of a platform supported thereon, such that sleeve portion 12 is disposed in an upright position. An opening 20 is provided in frame 18 below sleeve portion 12 of base 10, as best shown in FIGURE 2. An elongate pressure cylinder 22 extends through base 10 and opening 20 and is frictionally clamped to the former in a well known manner by bolts 24 which extend through and interconnect the flanges of sleeve portion 12 thereof. When thus secured, the greater length of cylinder 22 extends on that side of frame 18 opposite base 10, that is, below frame 18 as the apparatus is shown in the drawings.

Cylinder 22 is provided with upper and lower end caps or heads 26, 28, respectively, which may be secured thereto by any suitable means, such as by the flanged retainer ring assemblies 30 shown in FIGURE 2. Cylinder heads 26, 28 are provided with ports 33, 35, respectively, for the passage of pressurized fluid, such as air, to and from cylinder 22. Upper head 26 is also provided with a centrally located vertical bore, through which extends a rod 32 having its lower end secured to a piston 34 mounted for reciprocatory movement within cylinder 22 between heads 26, 28. O-rings 36 or the like are provided adjacent heads 26, 28 so as to prevent the passage of compressed fluid from cylinder 22 except through ports 32, 34, in a manner described subsequently herein.

The upper end of rod 32 is provided with a reduced portion 38 which, due to the length of the rod, is at all times disposed exteriorly of cylinder 22 irrespective of the position of piston 34 therein. A pair of spaced bearings 40 are disposed about and secured to reduced portion 38 of rod 32, as by means of a press fit between their inner races and the reduced end portion. If desired, a nut and washer 42 may also be provided in the upper end of rod 32 so as to additionally insure against bearings 40 being displaced from reduced portion 38 thereof. The outer races of bearings 40 are secured, as by means of a press fit, to and within the generally cylindrical stem portion 44 (see FIGURE 2) of a substantially T-shaped bracket member 46 (see FIGURE 1), such that stem portion 44 encloses and is concentrically disposed about the bearings and the upper length of rod 32.

60 By virtue of the construction thus far described, it will

65

70

be apparent that bracket 46 is secured to rod 32 for reciprocatory movement therewith, and for rotary movement relative thereto about the longitudinal axis of its cylindrical stem portion 44. The capability of bracket 46 for rotary movement relative to rod 32 is restricted, however, by means best shown in FIGURES 2 through 4. The means to which reference is made includes a collar 48 secured to and about reduced portion 38 of rod 32 below bracket 46, as by means of a set screw 50. Integral with and extending about approximately one-half of the circumference of collar 48 is an upstanding flange 52. Secured to and extending from the outer surface of stem portion 44 of bracket 46 is a pin member 54 which will engage the vertical edges of flange 52 upon rotation of bracket 46. It will be apparent that pin 54 and flange 52, particularly the vertical terminal edges of the latter, define co-operating stop means limiting rotary movement of bracket 46 to approximately 180 degrees. The extreme rotative positions of bracket 46 and its path of rotary movement are illustrated in FIGURE 4.

Means are also provided for resiliently maintaining bracket 46 in, and for returning it to, one of its extreme rotative positions. As best shown in FIGURE 3, a coil spring 56 encircling stem portion 44 of bracket 46 has one of its ends, identified by the numeral 58, secured to the bracket and its other end 60 secured to flange 52 of collar 48. When thus secured, spring 56 resiliently urges bracket 46 into the extreme rotative position thereof illustrated in FIGURE 3, and in FIGURE 4 by solid lines. Rotation of the bracket in the direction of the arrows to its other extreme rotative position, as shown by the arrows and dotted lines in FIGURE 4, coils spring 56. Upon release of the bracket, spring 56 will uncoil and return the bracket to the position illustrated in FIGURE 3, in a well known manner. The purpose and advantages of this feature are hereinafter discussed.

Bracket 46, in addition to cylindrical stem portion 44 already described, is provided with a horizontal bar position 62 having a pair of spaced upstanding flanges 64. An elongate upright hosiery form 66 having a free upper end portion 68 has its lower distal end 70 received between flanges 64 (see FIGURES 1 through 3). Suitable fastening means, such as bolts 72, extend through flanges 64 and lower end 70 of the form, and rigidly secure the form to and for movement with bracket 46. It will thus be apparent that form 66 is mounted for reciprocatory movement along a fixed vertical path and for rotative movement through approximately 180 degrees about its longitudinal axis, which is alined with the axes of stem portion 44, rod 32, and cylinder 22. The reciprocatory movement is illustrated in FIGURE 1, in which the form and bracket are shown in solid lines in their retracted position and by dotted lines in their projected position.

Form 66 may be positively reciprocated along its path of travel between the projected and retracted positions shown by means to be now described, and including a source of fluid under pressure. By reason of its economy and availability, air is a preferred fluid and the source 74 thereof schematically illustrated in FIGURE 6 may be a conventional type air compressor. A conduit 76 leads from air source 74 to the inlet side of a conventional four-way valve 78 which is housed within and actuatable by a foot treadle 80 positioned in convenient proximity to and operable by the foot of an operator of the apparatus, as shown in FIGURE 1. The outlet side of valve 78 includes an exhaust port 82, a second port 83 communicating with port 33 of upper cylinder head 26 by means of a conduit 84 and a fitting 86; and a third port 85 communicating with port 35 of head 28 by means of conduit 88 and fitting 100. The two positions of valve 78 and its actuating lever 104 are illustrated in solid and dotted lines in FIGURE 6. When valve 78 is in its solid line position shown in FIGURE 6, compressed air is conducted from source 74 through conduit 76, port 83 of the valve, conduit 84, fitting 86, port 33 of cylinder head 26 and to the interior of cylinder 22 where it forces piston 34 downwardly to its lower-

most position shown in FIGURES 2 and 6. Any air beneath piston 34 will be exhausted from cylinder 22 during its downward movement through port 35 of lower cylinder head 28, fitting 100, conduit 88, and ports 85, 82 of valve 78. Positioning of piston 34 in its lowermost position shown in FIGURES 2 and 6 will, of course, simultaneously position form 66 in its retracted position illustrated by solid lines in FIGURE 1. When valve 78 is moved to the position shown in dotted lines in FIGURE 6, which positioning would be accomplished by means of an operator utilizing foot treadle 80, air is directed from source 74 through conduit 76, port 85 of the valve, conduit 88, fitting 100, and port 35 of cylinder head 28 to urge piston 34 upwardly into engagement with cylinder head 26. The air above piston 34 is exhausted from cylinder 22 during upward movement of the piston through port 33 of head 26, fitting 86, conduit 84, and ports 83, 82 of valve 78. Upward movement of piston 34 as described projects form 66 along its path of travel to the dotted line position thereof shown in FIGURE 1. Valve 78 is resiliently maintained in its solid line position shown in FIGURE 6, wherein form 66 is maintained in its retracted position, by means of springs 102 (see FIGURES 5 and 6) contained within foot treadle 80 and operatively connected to 20 the actuating lever 104 of the valve.

In utilizing the apparatus of the illustrative embodiment of the invention, form 66 is initially disposed in its retracted position. With the form thus disposed, an operator positions the welt opening of a hose to be inspected 30 adjacent free end portion 68 of the form. Foot treadle 80 is then actuated by the foot of the operator to project form 66 along its path of travel and through the welt opening of the hose to its position shown in dotted lines in FIGURE 1. The welt opening of the hose is maintained substantially stationary by the operator as the form passes therethrough, as a consequence of which the hose is donned upon the form during its upward movement. If the welt opening of the hose is held by the operator during the donning operation in a position facing distal end 70 of form 66, the hose is donned upon the form in the manner described without being everted. If, however, the operator holds the welt opening of the hose in a position facing away from the distal end 70 of form 66 during the donning operation, then the hose will be simultaneously everted as it is donned on the form. 40 As will be recognized by those skilled in the art, such everting of the hosiery is frequently desirable. Once the hose is donned upon the form, it is inspected by the operator visually scanning the same. After scanning that side of the hose to which he is adjacent, the operator will 45 manually rotate form 66 about its longitudinal axis, as by grasping or pushing against a side edge thereof, so as to view the opposite side of the hose. The heretofore discussed stop means consisting of pin 54 and flange 52 of collar 48 limits rotation of form 66 to approximately 180 degrees, so that the opposite side of the hose is best positioned for viewing without the operator having to exercise undue care. After inspecting both sides of the hose on the form, the operator allows spring 56 to return the form to its original rotative position, and proceeds to doff the 50 hose therefrom. This is accomplished by actuating foot treadle 80 so as to retract form 66 while restraining the movement of the hosiery upon the form therewith, so that the form moves along its path of travel through and from the welt opening of the hose. Preferably the welt portion is held by the operator to restrain movement of the hose during doffing, since the welt is conveniently located adjacent the operator's hands. It will be appreciated, however, that if any portion, for instance the toe portion, of the hose is gripped during movement of the form to its retracted position the hose will be doffed therefrom. At 55 the conclusion of doffing, the inspected hose is placed in a suitable container and the operation is repeated, the apparatus being in both a proper rotative and reciprocatory position to receive the next item of hosiery.

From the foregoing description, it will be apparent that

the length of the stroke of form 66 may conveniently be approximately equal to the length of the hosiery to be inspected. If these lengths are exactly equal, and the donning operation is initiated by an operator positioning the welt opening of the hose in alignment with and at the same height as the terminal edge of free end portion 68 of the form, donning of the hose upon the form will be accomplished by movement of the form to its projected position without any movement of the welt portion of the hose whatsoever. With the same stroke, however, if the operation is initiated by the operator positioning the welt opening adjacent but a few inches above free end portion 68 of the form, then the operator must move the welt opening of the hose downwardly a corresponding few inches in order to completely don the hose upon the form. This downward movement may be performed as the form is moving upwardly, or after it is in its projected position. Or if the operation is initiated by the operator positioning the welt opening of the hose upon free end portion 68 of the form to a limited extent, and again assuming the stroke exactly equals the length of the hose, then the welt of the hose will be moved upwardly with the form during the last few inches of the stroke of the latter. Irrespective of which procedure is followed, it will be appreciated that at most only very limited movement on the part of the operator is required. Similarly, the benefits of the instant invention can be realized even though the stroke of form 66 is slightly greater or less than the length of the hosiery being inspected. Irrespective of which of the foregoing techniques is employed, the donning operation can be accomplished quickly, easily, and without undue operator fatigue since the welt of the hose is maintained substantially stationary.

In the drawings and specification there has been set forth a preferred embodiment of the invention and, although specific terms are employed, they are used in a generic and descriptive sense only and not for purposes of limitation, the scope of the invention being defined in the claims.

That which is claimed is:

1. Hosiery handling apparatus comprising a base, an elongate hosiery form, means carried by said base mounting said form for reciprocatory movement along a predetermined path between extended and retracted positions and for limited rotary movement about its longitudinal axis, means for resiliently biasing said form to a predetermined rotative position, and fluid pressure means operatively connected to said form for reciprocating the same.
- 10 2. Hosiery handling apparatus comprising a base, a pressure cylinder carried by said base, a piston mounted for reciprocatory movement within said cylinder, a rod connected to said piston for reciprocatory movement therewith, said rod extending from and having a portion disposed exteriorly of said cylinder, an elongate hosiery form, bracket means secured to one end of said form, bearing means interconnecting said bracket means and said exteriorly disposed portion of said rod, said form and said bracket being rotatably movable relative to said rod about the longitudinal axis of said form and being reciprocatorily movable with said rod relative to said cylinder along a predetermined path, co-operating means on said bracket and said rod limiting said form and said bracket to limited rotary movement between first and second extreme rotative positions, spring means carried by said bracket resiliently urging said bracket and said form to said first rotative extreme position thereof, and means for conducting fluid under pressure to said cylinder when desired so as to reciprocate said piston and thereby reciprocate said form along said predetermined path.
